UNITED STATES PATENT OFFICE.

ROBERT ROY LOCKHART, OF WINNIPEG, MANITOBA, CANADA.

ELECTRICAL WATER-HEATER.

1,091,582.

Specification of Letters Patent. Patented Mar. 31, 1914.

Application filed May 28, 1913. Serial No. 770,359.

To all whom it may concern:

Be it known that I, ROBERT ROY LOCKHART, of the city of Winnipeg, in the Province of Manitoba, Canada, have invented 5 certain new and useful Improvements in Electrical Water-Heaters, of which the following is the specification.

The invention relates to an electrical water heater and the object of the invention is to 10 provide an efficient, easily assembled electric water heater especially designed for use in connection with range boilers, the device being connected up with the usual heating pipes supplied on range boilers and provided 15 with feed wires fitted with a plug which can be readily screwed into a socket supplied for the purpose, the socket being connected in a suitable electric circuit.

With the above objects in view the invention 20 consists essentially in a cylindrical open ended casing, a contracted coupling piece screw threaded onto the upper end of the casing, a T-coupling piece screw threaded on the lower end of the casing, a screw threaded 25 plug closing the lower end of the T-coupling piece, a specially designed and constructed heating element carried by the plug and feed wires connected with the heating element, the parts being arranged and constructed as hereinafter more particularly described and later pointed out in the appended claim.

Figure 1 represents a side view of the device as it appears in use, parts being broken 35 away to expose construction. Fig. 2 represents an enlarged detailed vertical sectional view through the heater. Fig. 3 represents a horizontal sectional view through the heater. Fig. 4 is a plan view of the upper 40 end of the heating element.

In the drawing like characters of reference indicate corresponding parts in each figure.

1 represents an open ended cylindrical 45 casing having the ends thereof screw threaded to receive a contracted coupling piece 2 and a T-shaped coupling piece 3.

4 is a plug screw threaded into the lower end of the coupling piece 3 and closing the 50 same. The plug is supplied with an inwardly directed flange 5 which supports an insulating disk 6 on which is mounted the heating element 7. The heating element is now described in detail.

55 8 and 8' are two similar vertically disposed inner plates having their lower ends

connected by a base piece 9, which base piece rests on the disk 6 and is held permanently to the plug by a ring 10 which is screw threaded into the upper end of the plug and 60 is designed to jam the base piece and disk tightly against the flange 5. The plates 8 and 8' are connected by a series of staggered spaced tubes 11 having their ends opening to the outer sides of the plates. 65

12 represents a resistance coil of wire heavily insulated with an asbestos or such like coating 13 which insulated wire is wound backwardly and forwardly through the tubes on the left hand side, then across 70 and backwardly alternately through the tubes on the right hand side. The ends of the coil 12 are passed through the base 9 and also the disk 6 and are connected with feed wires 14 and 15. The wires pass downwardly through a suitable insulating ferrule 16 carried by the plug and are connected to a further electrical screw plug 17. The protruding portions of the coil appearing on the outer faces of the plates 8 and 8' are 75 enclosed by arched outer plates 18 and 19 having their edges suitably fastened to the edges of the plates 8 and 8'. The upper ends of the plates 8 and 8' 19 are closed over by cap plates 20 and 21. 80

The above completes the description of the heating element which it will be noticed fits snugly within the casing 1. 85

22 represents a range boiler mounted on a suitable pedestal 23 and supplied with the 90 usual feed water pipe 24 and service pipe 25.

26 and 27 represent the usual inlet and outlet heating pipes provided on a range boiler. The pipe 26 is connected through a suitable elbow 28 with a pipe 29 having the 95 lower end thereof screw threaded into the contracted upper end of the coupling piece 2 of the heater. The pipe 27 is connected through a suitable elbow 30 with a pipe 31 screw threaded into the coupling piece 3. 100

When one desires to heat the water in the range boiler he simply connects the plug 17 with an electrical receiving socket supplied for the purpose it being understood that the socket is contained within a suitable electrical circuit. When the connection is made the coil immediately heats the water within the casing, this establishing a circulation through the casing and boiler, the heated water passing into the boiler through the 105 pipes 26 and 29 and the cooler water into the pipes 27 and 31. When 110

the water in the boiler has been heated sufficiently the screw plug is detached and the circuit containing the coil so broken.

It will be seen that a very effective heater is provided as the water passing into the casing through the pipe 31 comes in contact with a large heating surface as it is forced to pass between the tubes which appear practically throughout the full length of the 10 casing.

What I claim as my invention is:—

The combination comprising a cylindrical casing, a contracted coupling piece secured to one end of the casing and provided with 15 an outlet opening, a second coupling piece secured to the opposite end of the casing and

provided with an inlet opening, an electrical heating element located within the casing and supported by the latter coupling piece and provided with a plurality of spaced 20 staggered radiating tubes and feed wires connected electrically with the element, said feed wires extending through said tubes and alternately entering and leaving opposite ends thereof, as and for the purpose speci- 25 fied.

Signed at Winnipeg this 30 day of April, 1913.

ROBERT ROY LOCKHART.
